CLAIM

The ornamental design for a display screen or portion thereof with transitional graphical user interface, as shown and described.

DESCRIPTION

FIG. 1 is a front view of the first image in a sequence of a first embodiment of a display screen or portion thereof with transitional graphical user interface, showing our new design;

FIG. 2 is a front view of the second image thereof;

FIG. 3 is a front view of the third image thereof;

FIG. 4 is a front view of the first image in a sequence of a second embodiment of a display screen or portion thereof with transitional graphical user interface, showing our new design;

FIG. 5 is a front view of the second image thereof; and, FIG. 6 is a front view of the third image thereof.

The appearance of the transitional image sequentially transitions between the images shown in FIGS. 1 to 3, between the images shown in FIGS. 4 to 6, respectively. The process or period in which one image transitions to another forms no part of the claimed design.

The outer perimeters illustrated by broken lines in FIGS. 1-6 depict a display screen or portion thereof and forms no part
